UNITED STATES PATENT OFFICE.

FRED HIRSH, OF NEW YORK, N. Y.

HOSE-SUPPORTER.

No. 919,168.

Specification of Letters Patent.

Patented April 20, 1909.

Application filed April 16, 1908. Serial No. 427,504.

To all whom it may concern:

Be it known that I, FRED HIRSH, a citizen of the United States, residing in the city of New York, in the county and State of New York, have invented certain new and useful 5 Improvements in Hose-Supporters, of which the following is a specification.

My invention relates to that class of hose supporters which encircles the leg above the, 10 calf and have a pendent end to which is attached a clasp or hose-grip device for securing or supporting short or half hose; and it has for its object to provide a simple, cheap, and efficient supporter of this class which will 15 be washable and renewable.

With this end in view, my invention consists, briefly stated, in making a hose supporter of a single piece of suitable material, preferably washable material, and in providing, 20 the same with metallic fastening, adjusting, and gripping devices all of which are easily attached thereto and removed therefrom.

In the accompanying drawing, Figure 1 is 25 a perspective view showing my improved hose supporter as it appears when in use and Fig. 2 is a perspective view of a similar hose supporter showing the strap disconnected and the metallic parts detached therefrom.

As thus shown, and in the form which I 30 now consider best adapted for the embodiment of my invention, the strap or band 1, which constitutes the main portion of the hose supporter and which is made of any suitable washable material, preferably a woven fabric without rubber, is at one end folded over upon itself and sewed down or otherwise secured to provide a loop 2, for the insertion of the middle prong of the three- 35 pronged metallic clip 3, by means of which this end of the strap is adjustably secured back upon the strap to regulate its length, as shown in Fig. 1. For a portion of its length, 40 at its other end, the strap is preferably made narrower by folding over and uniting its edges to form a flattened tube so that it can be bent sidewise more easily and without puckering up, and this end of the strap is also folded down and secured to itself to provide 45 a loop 5 for the attachment of the metallic hose-grip 6 the end of which is provided with an open slot 7 for the purpose. The clasp 8 by which the strap is secured around the leg is of the form patented by me in Letters Patent No. 783,039, under date of February 21st,

1905, and, as therein fully described, consists of a back or body plate which is curved up and back at one end and a front plate which is hinged at one end to the upper curved end of the back plate and provided with two lateral clamping jaws. This clasp 60 is adapted to its present use by forming the back plate with two lateral extensions or ears 9, at one end, and bending these ears back and around to form an open guideway 65 for the strap and by providing, at the other end, an open slot 10 similar to that at the end of the hose-grip by means of which guideway and slot the clasp is adjustably secured to the outer strip of the doubled end of the 70 strap.

In making use of the hose supporter, the strap is passed around the leg, the narrow end is brought over into the hook formed by the curved back plate of the clasp and the 75 hinged front of the clasp is then swung down into locking position, as shown in Fig. 1, and the hose-grip is secured to the hose.

The advantages of my improved hose supporter are obvious. Whenever the strap 80 becomes soiled the metallic fasteners can be easily removed, the strap washed, and the fasteners then put back in place; and the metallic fasteners, which represent the greater part of the cost of hose supporters of 85 this class, do not become useless when the strap is worn out, but can be used for an indefinite length of time by providing or obtaining extra straps and substituting a new one for that which has been worn out. 90

While I have shown and described above what I now consider as the best forms of gripping, adjusting, and fastening devices for use with my improved hose supporter, it will of course be understood that other 95 suitable and well known forms may be substituted in place of each or all of them and that other means may be employed for making them readily adjustable to and detachable from the strap without departing 100 from the spirit or sacrificing the advantages of my invention. Such other modifications may also be made as fall within the scope of the appended claims.

What I claim is new, and desire to secure 105 by Letters Patent, is—

1. A hose supporter which comprises a strap and means detachably connected therewith for securing one end of the strap to the hose and means detachably connected 110

2
to the other end of the strap adapted to engage an intermediate portion of said strap and secure it around the leg.

2. A hose supporter which comprises a strap adapted to pass around the leg and leave a pendent end and means for adjustably securing the strap around the leg and for securing its pendent end to the hose all detachably connected with said strap.

10 3. A hose supporter which comprises a single strap of washable material adapted to pass around the leg and leave a pendent end to be secured to the hose and metallic fasteners for adjusting the length of the strap, securing it around the leg and adjusting its pendent end to the hose, all detachably secured to said strap.

15 4. A hose supporter which comprises a single strap of washable material made

narrow at one end and detachable means for 26 securing the narrow end of the strap to the hose and its other end around the leg.

5. A hose supporter which comprises a single strap of washable material made narrow at one end, a detachable clip for securing the broad end of the strap back upon itself to form an adjustable loop, a detachable hose-grip for securing the narrow end of the strap to the hose, and a detachable clasp for securing the looped end of the 25 30 strap to the narrow portion thereof.

In witness whereof, I have signed my name in the presence of two witnesses.

FRED HIRSH.
